Primary Examiner—Ian Simmons*(74) Attorney, Agent, or Firm*—Knobbe Martens Olson & Bear LLP(57) **CLAIM**

The ornamental design for an anchor pad, as shown and described.

DESCRIPTION

FIG. 1 is an isometric view of an anchor pad showing my new design;

FIG. 2 is a top plan view thereof;

FIG. 3 is a bottom plan view thereof;

FIG. 4 is a rear elevational view thereof;

FIG. 5 is a front elevational view thereof; and,

FIG. 6 is a right side elevational view thereof, the left side being a mirror image thereto.

The broken line showing of the wells and release layers in the FIGS. 1, 2, 4, 5 and 6 are for illustrative purposes only and forms no part of the claimed design.
